UNITED STATES PATENT OFFICE.

DAVID T. OWEN AND WESLEY G. LEHMANN, OF CLEVELAND, OHIO; SAID LEHMANN
ASSIGNOR TO SAID OWEN.

SPRING STRUCTURE.

Application filed September 22, 1922. Serial No. 589,750.

To all whom it may concern:

Be it known that we, DAVID T. OWEN and WESLEY G. LEHMANN, citizens of the United States, residing at Cleveland, in the 5 county of Cuyahoga and State of Ohio, have invented certain new and useful Improvements in Spring Structures, of which the following is a specification.

This invention relates to spring cushions, 10 seats and bed mattresses and the object of the invention is to provide a spring structure in which the end coils of a series of helical wire springs are rigidly connected to move and yield unitedly or in a joint manner without independent pivotal play at their joints 15 or where connected, and a further object is to provide a simple and effective mode of clipping the springs together and kinking and bending the wire spring within the clip 20 itself to obtain a rigid connection and to prevent the wire from turning in the clip.

In the annexed drawing, Fig. 1, is a top view on a reduced scale, of a spring cushion fabricated according to our invention, and 25 Fig. 2 is a perspective view of one of the helical wire springs used in said fabricated spring structure. Fig. 3 is a sectional view showing the upper convolutions only of several springs clipped rigidly together, the 30 dotted lines in this figure showing the same convolutions depressed and all lying in the same inclined plane. Fig. 4 is a top view showing segmental portions of two wire springs united together by a clip, and Fig. 5 is a vertical section of the clip on line 35 5—5 of Fig. 4. Fig. 6 is a vertical section on line 6—6 of Fig. 4. Fig. 7 is a bottom view of the parts shown in Fig. 4. Fig. 8 is a perspective view of the clip and spring segments shown in Fig. 4. Fig. 9 is a perspective view of the same clip crimped longitudinally as well as transversely.

Our conception involves the fabrication of a plural number of helical or convolute wire 45 springs 2 into a unitary cushion, mattress or bed bottom, the springs being arranged upright in close formation parallelly in rows and connected together where nearest adjacent at their upper ends or at both their 50 upper and lower ends, these ends 3 being substantially circular and the largest coils or convolutions in the spring. We are aware that it is a common practice to join or unite such springs by clips, wires and 55 cords, but in such fabrications the springs

are either loosely and pivotally connected or have independent play in respect to each other where joined together. Where metal ties are used the play and movement between the parts produce a squeak or objectionable noise, and single springs are easily displaced and distorted. The cord ties permit displacement and distortion also, and these deteriorate, wear and break more quickly than metal ties. In lieu of fabricat- 60 65 ing the springs 2 in that manner we employ metal connecting clips 4 which become rigid immovable parts of the springs and unite all the loop ends of the springs rigidly together, thereby providing a substantially flat 70 horizontal surface which is depressed at any particular place or spring will distribute the load to the contiguous springs and beyond these bounds to the surrounding springs without sharp tilt or deflection of any one 75 of the springs.

Each clip 4 is made of a flat strip of metal having its opposite sides 5—5 curled around the wire loop ends 3—3 of adjacent springs, thereby uniting the adjacent springs in closely spaced relation. Then to lock the clip and springs together and prevent turning of the wire within the curled ends 5, the clip is indented and offset transversely at its curled ends thereby forming a corresponding indentation and offset 7 in the wire, see Fig. 6. The indentation in the clip may extend entirely across the top from side to side as shown in Fig. 8 so that the main body as well as the curled ends will be offset. Crimping of the wires and clip together locks the wires from turning in the curled ends, or vice versa, prevents the clip from turning on either wire. The corresponding loop ends of the springs are therefore held rigidly in 80 85 90 the same horizontal plane and inasmuch as each spring is rigidly united at three or four radial points with the springs contiguous thereto all the loop ends of the springs are stiffly and rigidly held and connected and no single spring is free to twist or turn at its top and be deflected to any material extent out of horizontal alignment with the tops of contiguous springs. In placing a load at some spot on the spring structure this spot 95 will be depressed more than in any other place, but the same pitch or slope will be imparted to all of the rigidly connected top loops within the adjacent areas, thereby distributing the load evenly to all of the springs 100 105 110

surrounding without buckling the springs laterally. The action occurring in the top surface of the fabric is similar to the flexing of a thin flat sheet of metal, but of course the 5 wire structure is more flexible.

In Fig. 9 we show a slightly modified form of clip 4' which is indented and offset transversely in the same way as in the clip hereinbefore described, but a longitudinal 10 indentation 8 is also made therein between the curled edges 5—5. Crossing of the indentations in this way makes a stiffer clip and a stronger lock for the offset or kinked 15 portions of the spring-wire loops 3. In both forms of the invention the offsets in the wire extend downwardly at right angles to the horizontal end loop of the springs and are locked from turning in the clip. The top of 20 each spring thus becomes a rigid part of the tops of the adjacent springs, and whatever flexure there may be is in the wires between the clips. If desired the clips and wires may be rigidly united together by welding or 25 brazing methods.

25. What we claim is:

1. A spring structure, comprising adjoining wires and metal connecting clips therefor, said clips and wires being locked in rigid union where connected together by 30 indentations formed in both the wires and clips.

2. A spring structure, comprising a plurality of wire springs, metal clips connecting adjacent portions of said springs, said

clips and the wires being both indented 35 transversely at each connecting place therein.

3. A spring structure, comprising parallel rows of wire springs arranged closely adjacent each other, and metal clips connecting 40 said springs having transverse and longitudinal indentations effecting rigid interlocking of said springs.

4. A spring structure, comprising separate wires connected by metal pieces curled around the wires, a curled portion and the 45 wire therein being both indented at right angles across the same.

5. A spring structure, comprising wires, and a clip for adjoining wires indented lengthwise intermediate the wires and also 50 indented transversely into the wires.

6. A spring structure comprising adjoining wires and a metal connecting clip therefor, said clip and one of said wires being locked in rigid union where connected together by 55 an indentation formed in both the wire and the clip.

7. A spring structure, comprising juxtaposed wires, and a clip connecting said wires having a curled portion sleeved upon one of 60 said wires and offset together with the wire to provide a crank portion in the wire within a crank portion in the clip.

In testimony whereof we affix our signatures.

WESLEY G. LEHMANN.
DAVID T. OWEN.
